UNITED STATES PATENT OFFICE.

PAUL A. HOUGHTALING, OF RIVERTON, NEW JERSEY, ASSIGNOR TO THE CURTAIN SUPPLY COMPANY, OF NEWARK, NEW JERSEY, A CORPORATION OF NEW JERSEY.

CURTAIN-FIXTURE.

No. 909,186.

Specification of Letters Patent.

Patented Jan. 12, 1909.

Application filed June 29, 1905. Serial No. 267,478.

To all whom it may concern:

Be it known that I, PAUL A. HOUGHTALING, a citizen of the United States, residing in Riverton, New Jersey, have invented certain Improvements in Curtain-Fixtures, of which the following is a specification.

My invention relates to a novel device for frictionally holding a shade or curtain in a given position against the tendency of its 10 spring roller to roll it up or raise it, more particularly having to do with that special type of curtain structures in which the lower portion of the curtain is provided with friction devices engaging the bottoms of the grooves 15 in the window frame in which the curtain operates.

One object of the invention is to provide a relatively simple and inexpensive structure designed to be applied to the lower portion 20 of a curtain, which shall automatically hold said curtain in any given position against the tendency of its spring roller to raise it; it being also desired to so construct the device that its unauthorized removal from the 25 grooves of the window frame will be prevented. These objects I attain as herein-after set forth, reference being had to the accompanying drawings, in which:—

Figure 1, is a vertical section of a curtain 30 rod and the heads or boxes carried thereby, illustrating the construction of one form of my invention; Fig. 2, is a vertical section of a curtain rod and one of the heads or boxes carried thereby, illustrating a modification 35 of the invention, and Fig. 3, is a vertical section similar to that shown in Fig. 2, illustrating the various parts of the device in the positions occupied by them when holding the curtain and its rod in a given position 40 against the upwardly acting tendency of the spring curtain roller.

Referring to Fig. 1, of the above drawings, A represents a tubular curtain rod of the well known construction, commonly carried 45 in the lower portion of a curtain, and on each end of this is a spring actuated bar B carrying a head or box C; the spring b for acting on each of said bars being held within the curtain rod in any desired manner. Rotatably carried within each head or box is a roller D having its spindle d journaled in the sides or cheek pieces of the box and each roller has upon it what may be called a tire or tread d' of resilient material. This tread 55 consists of an endless band of such length

that a definite portion of it, as d², normally projects beyond or outside of a circular form and out of engagement with the roller. In other words, while the general shape of the tread is circular, it is so made that a certain 60 portion of it does not engage or project beyond the surface of the roller D, though its remainder grips said surface frictionally with a greater or less force depending upon the design.

It will be understood that under operating conditions a spring curtain roller constantly tends to move the curtain rod A and the heads C, with their attached parts, toward the top of the window frame, and if 70 the curtain be not held by some external force, the roller D, and with it the tread d', will be turned until the projecting portion d² of said tread comes between the roller and the surface D forming the bottom of the 75 groove in the window frame. The two heads or boxes C are normally pressed away from each other into engagement with this surface by means of the springs b and the resilient material of the tread is of such a 80 nature and dimensions that when the roller has turned to the position above noted, its projecting portion d² wedges or jams between the body of the roller and the adjacent surface E of the window frame groove. 85 This at once prevents further upward movement of the curtain rod and curtain. If, however, external force be applied to the curtain rod to move it upwardly, the roller D and its tread are forced to revolve, and 90 the projecting portion d² is temporarily compelled to assume a curved form concentric with the spindle b, while some other part of the tread d is temporarily forced away from the surface of the roller D. As soon, however, as the roller has revolved sufficiently 95 to cause the portion d² of the tread to pass out of engagement with the surface E of the window frame groove, said portion immediately assumes its former shape, and the 100 temporarily distorted circular part of the tread again moves into engagement with the surface of the roller.

It is of course to be understood that the structure of head described can be applied 105 to other forms of rods or by other means be attached to the curtain without departing from the invention.

In order to prevent unauthorized removal 110 of the curtain rod from the grooves of a win-

dow frame, I may extend the ends of the heads or boxes C so that they project some distance above and below the rollers D, as indicated at c. It will thus be seen that 5 should the curtain rod A be inclined to the horizontal in an endeavor to remove it from the window frame grooves, an end c of each of the heads or boxes will engage the bottoms of the two grooves so that such removal 10 cannot be accomplished under the usual or ordinary manner of manipulation.

In that form of my invention shown in Figs. 2 and 3, I provide one or more spindles d³, which are preferably non-rotatably held 15 in the heads or boxes C'. Frictionally engaging the surface of each spindle is a split ring or cylinder d⁴ which is fixed by means of a pin d⁶ to a ring or roller d⁵ of resilient material in such manner that the center of the spindle is eccentric to the center of said roller. 20

As in the case shown in Fig. 1, it is immaterial as to whether the bars B are or are not movable relatively to the curtain rod A; for, in any case, if the curtain be moved a short 25 distance upwardly under the action of its spring roller, the various parts will move from the positions shown in Fig. 2 to the positions shown in Fig. 3. Since the distance between the center line of the spindle and the 30 surface of the bottom of the groove E is to all intents and purposes invariable, the rotation of the roller d⁵, because of its frictional engagement with the surface E of the window frame groove, tends to move the split ring d⁴ off of the said spindle. This tendency, however, is resisted by the split ring, which is also of resilient material, and also by the roller d⁵, so that as a result said roller 35 is pressed against the surface of the groove with sufficient force to prevent the continued 40 upward movement of the curtain. It will be understood, however, that if external force be applied, the split ring d⁴ is further forced off of the spindle d³ and the spring 45 roller d⁵ is distorted from its normal shape to permit of such movement, although when the curtain is released both of these parts act to prevent further movement of the curtain under the action of its spring roller.

50 In the case illustrated in Figs. 2 and 3, I have shown two rollers in each of the heads or boxes, although it will be understood that this arrangement can be altered if desired, without departing from my invention.

55 I claim as my invention:

1. In a curtain holding device, the combination with a stick, of a head at the end thereof, a rotatable member carried by and resiliently held in the head, a portion of the 60 tread of said member being free, whereby the same may be moved toward and from its axis.

2. A curtain holding device consisting of a curtain rod, heads carried thereby, and 65 revoluble structures carried by the heads, a

resilient ring having portions of its surface at different distances from the axis of revolution thereof mounted on each of said structures and being otherwise free and unconnected, in combination with a guiding frame 70 engaged by said resilient ring.

3. A curtain holding device consisting of a curtain rod, heads thereon, in combination with a guiding frame, substantially cylindrical rollers carried by the heads, and a tread, 75 one for each roller, of resilient material engaging the surface thereof, a portion of the tread being out of engagement with its roller and projecting beyond the remainder of the tread, substantially as described. 80

4. A curtain holding device consisting of a curtain rod, and substantially cylindrical and revoluble structures each having a resilient projection and carried by the ends of the said rod, substantially as described. 85

5. A curtain holding device consisting of a curtain rod, spring actuated bars carried thereby, each bar having a head, and a substantially cylindrical structure carried by each head, each of said structures having a 90 resilient tread provided with a portion projecting for a greater distance from the axis of revolution of the structure than the remainder, substantially as described.

6. In a curtain fixture, the combination of 95 a stick, a head at the end thereof, and a resiliently held rotatable member in the head adapted to engage the window frame, said member having portions of its tread at different distances from its axis of rotation and 100 adapted to resist rotation along the window frame.

7. In a curtain fixture, the combination of 105 a stick, a head at the end thereof, and a rotatable and resilient member mounted in the head adapted to contact with the window frame and having a projection for yieldably resisting rotation along the window frame.

8. In a curtain fixture, the combination of 110 a stick, a head at the end thereof, and a rotatable member in the head adapted to engage the window frame, a tread and journal for the rotatable member, and a yielding engagement between the inner surface of the tread and its journal to yieldably resist rotation along the window frame. 115

9. In a curtain fixture, the combination of 120 a stick, a head at the end thereof, and a rotatable member in the head adapted to engage the window frame, a tread and journal for the rotatable member, and a resilient engagement between the inner surface of the tread and its journal.

10. In a curtain fixture, the combination of 125 a stick, a head at the end thereof, a rotatable member in the head adapted to engage the window frame, a journal for the rotatable member, said rotatable member being resiliently connected to its journal.

11. In a curtain fixture, the combination 130

with a stick, of a head at the end thereof, a journal in the head, a rotatable member adapted to contact with the window frame having portions of its tread at different distances from its axis of rotation and unconnected therewith and adapted to resist rotation along the window frame, and a resilient engagement between the inner surface of the tread and its journal.

10 12. In a curtain holding device, the combination with a head, a rotatable member on the head, having a yielding projection ex-

tending beyond the regular surface of the rotatable member and adapted to be wedged between the body of the member and the window frame guide for interrupting the rotary movement of the member.

In testimony whereof, I have signed my name to this specification, in the presence of two subscribing witnesses.

PAUL A. HOUGHTALING.
